UNITED STATES PATENT OFFICE.

JOSEF PLEBANSKI, OF WARSAW, POLAND.

DIRECTIVE ANTENNA SYSTEM.

Application filed February 15, 1924, Serial No. 692,964, and in Russia July 10, 1918.

Application for this invention has been filed in Russia July 10, 1918, and in Germany, August 25, 1922.

The radio stations in operation up to the present time, both for wireless telegraphy and for wireless telephony, are based on the following method:

The electrical energy is stored in large quantities in a closed oscillatory circuit and is then transmitted to an open oscillatory circuit (aerial), from which it is further radiated. The coupling of closed and open oscillatory circuits has become so common that hardly a radio telegraphic station will be found without these two circuits.

The same method is also generally used at receiving stations. For receiving the electromagnetic energy of an electro-magnetic wave open oscillatory circuits (aerials) are used; the conversion of the high frequency energy into other forms of energy, however, takes place in closed circuits. Successful attempts have, however, already been made to use closed oscillatory circuits for receiving (frame aerials).

It has long been known that open oscillatory circuits have the following disadvantages:

1. As is well known, the useful output of an aerial depends on the ratio of the radiating power to the power expended in the aerial in covering various losses. In the case of an open aerial or in the ground these losses (earthing, counterpoise and the like) are very great.

2. In converting energy from closed to the open oscillatory circuit a considerable part of the energy is lost.

3. In transmitting a radio signal it is generally desirable to send out the whole of the energy radiated from the transmitting aerial only in the direction of the receiving aerial. In the case of transmitting aerials as used at the present time the energy is radiated almost uniformly in all directions.

It has been found that the coupling of closed and open oscillatory circuits, which has hitherto been regarded as essential and which has the above mentioned disadvantages, can be replaced by suitably arranged and interconnected closed oscillatory circuits of a special form, which radiate the energy directly. Although a closed oscillatory circuit has a far smaller radiating power than

an open oscillatory circuit, the same "efficiency of the aerial" can obviously be obtained with it as with an open aerial, if the losses are sufficiently reduced. If a closed oscillatory circuit is constructed in such a manner that its radiation decrement becomes approximately equal to the loss decrement, the same favourable conditions can be obtained as with an Alexanderson, Meissner or Eckersley aerial. Since the resistance of a closed oscillatory circuit depends to a far less extent on the ground, weather and the like conditions, it will be easier to obtain small resistances with it, so as to approximate more closely to the desired efficiency of the aerial. A great advantage may, however, also be obtained, namely, the directional effect. The energy is radiated mostly in one direction (unilateral) or in two directions (bilateral F-forward and rearward direction), this results both in a great saving of energy and also in eliminating the possibility of disturbances (in receiving) and it is also possible to keep the transmission secret.

The transmitters with closed oscillatory circuits as hitherto proposed were unsuccessful in practice, as their radiating power was only very small or rather as the losses were enormously great as compared with the useful radiation. The cause of this was in the first place the bad construction of the closed oscillatory circuits. In order that large quantities of energy may be radiated, the wave length must be kept correspondingly short and the capacity increased. These two conditions, however, counteract one another, since on the one hand the increase of capacity results in the increase of the wave length and on the other hand the shortening of the wave length is obtained substantially by reducing the capacity. According to Flemming the radiation of a closed oscillatory circuit (magnetic vibrator) is inversely proportional to the fourth power of the wave length. It is thus obvious, that in order to obtain a short wave length, some experimenters had to reduce the capacity of the circuits and thereby diminished at the same time the energy radiated. If they increased the capacity, the wave length became too great and the radiation became small.

The fundamental condition for a great

energy radiation has been solved by the inventor in the following manner illustrated in the accompanying drawings in which:—

Figure 1 shows three loops connected in parallel angularly spaced apart relation.

Figures 1^a, 1^b, and 1^c are modifications of Figure 1.

Figures 2 and 3 are diagrams showing the polar curve of reception or transmission of the antennæ.

Figures 4 and 5 are modifications of Figure 1.

Figure 6 is a detailed showing of switching arrangement adapted to be used with a plurality of circuits as shown in Figure 1.

Two or more closed circuits of sufficiently large dimensions are used, which are connected to one or more capacities and self-inductances, that is, one coating of the condenser or condensers is connected to the starting point of all the circuits, while the other coating is connected to the other ends of the circuits, self-inductances being inserted if necessary (Fig. 1). It is obvious, that the capacity or self-induction (capacities or self-inductances) may be introduced anywhere in the circuits, for instance the capacity or self-induction formed by the aerials themselves can be used, as shown in Fig. 1.

Each of these closed circuits has the form of a polygon in space, while in certain cases the polygons may be developed in one plane and have for instance the form of a triangle.

The advantages of this method are as follows:—

(1) A closed oscillatory circuit with as small a decrement as desired is obtained.

(2) By connecting in parallel or setting up in parallel a number of such circuits the wave length is reduced the capacity common to all of the circuits remaining constant. Thus an oscillatory circuit can be constructed without difficulty which has a relatively small wave length and comprises a large capacity in order to radiate a great amount of energy.

(3) The influence of the ground and weather conditions becomes for smaller than with open aerials.

(4) The form of the polygons in space may vary. Among other forms that of a triangle or trapezoid appears to be very practical. Such circuits can easily be suspended on a single mast.

Fig. 1^c shows polygons each of which consists of two triangles.

When a plurality of such triangular, trapezoidal or rectangular oscillatory circuits are used, the circuits being relatively displaced through a certain angle, the characteristic of the long distance effect will be particularly sharply defined and approximates to the form of a triangle (Fig. 3).

This characteristic is taken from an actual

case. It is to be noted that in Figure 4 of the drawing only one half of the character is represented in order to save space.

The circuits connected up in parallel can be caused to oscillate in a known manner, that is either indirectly (primary circuit—secondary circuit, Fig. 5) or directly (Fig. 5); it is of course immaterial which is adapted for producing the oscillations; a spark gap, a high frequency machine or a valve transmitter may be used.

The advantages of this method can be readily seen from this characteristic.

In order to make it possible to telegraph or telephone in any direction, the closed polygons, which are connected in parallel, may be switched in in groups (if similar systems or polygons are erected in all directions) by means of a suitable commutator (Fig. 6). The number of possible directions will be equal to the number of polygons, but not to the number of systems.

According to the present method it is thus possible to obtain different characteristics of the long distance effect as desired.

If the oscillatory circuits are erected in such a manner that the coupling between them becomes zero, for instance one group at right angles to the other, they will be suitable for duplex working, as the oscillations in one circuit (transmitter) do not have any effect on the other circuit.

The aerial conductor system can be connected either as a secondary system to any radio station in place of the usual aerial and counterpoise or earth (Fig. 4) or the oscillatory circuits may be used directly as the primary and end system, by the generator of the oscillations (spark gap, high frequency machine, anode circuit of the tube transmitter and the like) being connected up directly in the aerial system.

The same method can be used for receiving (directional receiving). As compared with the frame-aerials used at the present time the new system has a more favourable characteristic of the long distance effect (which is important for radio goniometry) and a greater receiving intensity. As compared with the Beverage aerials the new system has the advantage of smaller dimensions and the possibility of varying the receiving direction, the characteristic of the long distance effect being also more favourable.

Having now described my invention, what I claim as new and desire to secure by Letters Patent is:—

1. A wireless receiving and transmitting aerial comprising a plurality of oscillatory circuits in the form of polygons adapted to be connected in parallel in a capacity circuit, a commutator for closing said circuits, and a group connector operable between the commutator and said circuits for closing

the same through the commutator in groups selected from the plurality of circuits.

2. A transmitting and receiving aerial for wireless telegraphy and telephony comprising a series of oscillatory circuits adapted to be connected in parallel relation with respect to one another, a capacity circuit, a commutator for closing said circuits in the capacity circuit, and a group con-

nector adapted to traverse the commutator 10 and said plurality of circuits for selectively connecting groups of the circuits with the commutator.

In testimony whereof, I have signed my name to this specification at Warsaw, 15 Poland, this 24th day of January, 1924.

JOSEF PLEBANSKI.
